UNITED STATES PATENT OFFICE

162,268

CABINET FOR A HEATER OR THE LIKE

Lawrence H. Wilson, Detroit, Mich., assignor to
Motor Wheel Corporation, Lansing, Mich., a
corporation of Michigan

Application September 12, 1950, Serial No. 12,158

Term of patent 14 years

(Cl. D81—19)

To all whom it may concern:

Be it known that I, Lawrence H. Wilson, a citizen of the United States, residing at Detroit, in the county of Wayne and State of Michigan, have invented a new, original, and ornamental Design for a Cabinet for a Heater or the Like, of which the following is a specification, reference being made to the accompanying drawing, forming part thereof.

Fig. 1 is a perspective view of a cabinet for a heater or the like, showing my new design.

Fig. 2 is a front elevation of the cabinet.

Fig. 3 is a side elevation of the cabinet.

Fig. 4 is a top plan view of the cabinet.

Figs. 5 and 6 are sections along the lines 5—5 and 6—6 respectively of Fig. 4.

The side of the cabinet not shown is substan-

tially the same as the side shown and the back of the cabinet is plain.

I claim:

The ornamental design for a cabinet for a heater or the like, substantially as shown and described.

LAWRENCE H. WILSON.
